UNITED STATES PATENT OFFICE.

ARCHIBALD A. DICKSON, OF TORONTO, CANADA.

PRESS.

SPECIFICATION forming part of Letters Patent No. 624,630, dated May 9, 1899.

Application filed June 6, 1898. Serial No. 682,724. (No model.)

To all whom it may concern:

Be it known that I, ARCHIBALD A. DICKSON, a subject of the Queen of Great Britain, and a resident of the city of Toronto, in the county 5 of York and Province of Ontario, in the Dominion of Canada, have invented certain new and useful Improvements in Presses, of which the following is a specification.

This invention relates to machines for compressing and consolidating such materials as cold dry peat and substances possessing similar characteristics as to resistance and varying density into blocks; and it consists in certain improvements upon or further developments of the press described in my United States Patent No. 613,856, dated November 8, 1898, having for their principal object a material increase in the speed of operation and output of the machine.

10 The improvements may be said to consist, chiefly, in the location of the power device between the crank or driving shaft and the forming-dies; in the direct application of the power of a steam-cylinder, piston, and piston-rod to the formers or male dies; in the construction and means of adjustment of the die-block, the construction of the piston and the formers, and in other details and combinations of parts, as will be fully set forth in the 15 following description and pointed out in the claims.

20

25

30

For a full comprehension of the invention reference must be had to the accompanying drawings, forming part of this specification, in which similar letters of reference indicate like parts.

In said drawings, Figure 1 is a front view, partly in section, of a vertical press embodying my invention. Fig. 2 is an end view of 40 the same, partly in section and with parts of the framing broken away, on the line 2 2, Fig. 1. Fig. 3 is a sectional plan taken on the line 3 3, Fig. 1. Fig. 4 is a plan of the piston-rod guide. Fig. 5 is a sectional plan of 45 the die-block and its connections. Fig. 6 is a longitudinal section of the die-block and its supporting-frame. Fig. 7 is a plan of same, showing one-half of the retaining-plate. Fig. 8 is a side view of the die-block, showing one 50 means of connecting the die-rods thereto. Fig. 9 is a similar view, but partly in section, illustrating means whereby vertical adjust-

ment of the die-block upon the tie-rods may be effected. Fig. 10 is an enlarged detail showing one form of male die and its tip; and 55 Fig. 11, a sectional detail of a modified form thereof, whereby the male-die tip may be adjusted to vary the length of stroke between the male and female die members. Fig. 12 is a sectional elevation of a preferred form of 60 piston and piston-rod connection.

The main features of a vertical press constructed according to my present improvement are formers or male dies in rigid connection with the projecting lower ends of the 65 piston-rods of vertically-arranged steam-cylinders, cross-heads and connecting-rods in connection with the projecting upper ends of the same piston-rods, a crank-shaft, (acting as a balance and driving-shaft,) bearings 70 therefor independent of the main frame, and tie-rods extending downward from such bearings and connected to an independent die-block provided with forming-tubes or female dies registering with the formers or male dies, 75 such tie-rods also intermediately supporting the steam-cylinders, cross-head and piston-rod guides and being stayed in the main frame.

The formers or male dies serve to impart a vertical compression to charges of material 80 successively gravitating into the upper ends of the forming-tubes or female dies by successive strokes, each stroke forming a block upon the yielding base offered by the blocks previously formed and remaining within the 85 female-die member, a single resistance-block being inserted at the commencement of the operation in order to prevent the first charge of loose material from falling out at the lower end and so as to afford a base for the formation of the first condensed block. The alternate action of a pair of formers results in the 90 formation of a new block within the upper end and the simultaneous forward progression or ejection of a previously-formed block 95 at the lower end of one tube (the whole contents thereof having a forward progression) and the gravitation at the same time of a fresh charge of material between the other pair of die members ready for compression 100 as the first-named former recedes.

A A are two legs (preferably of channel-iron) forming the main frame, serving to carry the dead-weight and to stay and steady the

operative parts, these legs having bolted thereto or otherwise formed thereon any suitable number of clamps *a a* for steadyng and supporting the dead-weight of the tie-rods 5 hereinafter mentioned.

B is a crank-shaft located at the head of the machine, carrying two fly-wheels *b b*, one on each extremity, and formed with two cranks *b'* and *b''*, the pins of which carry the 10 upper ends of connecting-rods *C C'*, which are pivoted at their lower ends to cross-heads *c c'*, working in proper ways in a guide-bar *D*, supported by clamps *d d*, engaging the three rear tie-rods to be presently described, as seen 15 in Figs. 2 and 3.

Bearings *E*, *E'*, and *E''* are provided for the crank-shaft, the two former being situated outside of the cranks and close to the fly-wheels and the latter being located midway 20 between the cranks. These three bearings are preferably yoked by a crown-piece *E''* (indicated by dotted lines in Fig. 1) and are entirely independent of the main frame or legs, being supported at their under sides 25 by means of collars or enlargements *f f' f''*, one on each of three pairs of vertically-arranged tie-rods *F F' F''*, passing through both lower and upper parts of said bearings and having threads and nuts upon their upper 30 ends to hold the journal-sections firmly and closely together. These tie-rods extend downward from the bearings to within a short distance from the floor-base of the machine and besides being clamped at any required number 35 of points *a a* to the legs *A A* to steady and support the parts these rods pass through eyes *g g' g''* in the die-block *G*, (in which are located the forming-tubes or female dies, as hereinafter specified,) being provided with 40 collars, threads, and nuts similar to those on their upper ends, as shown in Figs. 1, 2, and 8, for effecting the firm support of the die-block, or when it is desired that the die-block 45 may be capable of vertical adjustment the threads may be extended or increased and nuts *g g'* be placed thereon to bear both upon the upper and lower faces of the die-block *G*, as seen in the modification, Fig. 9.

H H' are two steam-cylinders arranged intermediate of the cross-head guide-bar *D* and the die-block *G*, being held in position by the three pairs of tie-rods which pass through brackets cast upon said cylinders and afford support and steadiment therefor through the 55 medium of collars and nuts on said rods, all as shown in Figs. 1, 2, and 3.

In every case where I have shown integral collars upon the tie-rods it will be understood that I may substitute threads and nuts with 60 corresponding effect.

The cylinders *H* and *H'* have brackets *h h'*, engaging the tie-rods, as shown in Figs. 1, 2, and 3, being supported by the collars *x x'* and retained by the nuts *x x'* on said rods.

65 These cylinders have any suitable type of pistons *I* and *I'*, connected to the piston-rods *J* and *J'*, respectively, such as the single-piece

piston, having the retaining-nuts shown in Figs. 1 and 2, but as the minimum length of cylinder and weight of metal and the greatest 70 possible rigidity and security of fastening are so desirable in a machine of this class I prefer to adopt the construction shown in Fig. 12. Here the piston-rod is provided with an integral collar *j*, and the piston is made in two 75 longitudinal pieces, with close meeting faces and each having a proper peripheral packing-ring *j'* and a ground recess (or enlargement of the bore) in the center to receive the collar *j*, as well as a third packing-ring *j''* at the 80 joint, the two portions of the piston being held securely together and tight upon the rod and its collar by means of any suitable number of bolts or studs *b b*, having countersunk heads and nuts. This arrangement allows 85 the stroke to bring the piston very close to the cylinder-heads, and thus effect the economy and advantages named.

The piston-rods *J* and *J'* project through both cylinder-heads, their upper ends forming connection with the cross-heads *c* and *c'* and terminating below in formers or male dies *K* and *K'*, respectively. These latter are provided with hardened tips *k*, the shanks of which are preferably recessed in the former 95 ends and firmly secured therein by one or more screws *k'*.

To vary the length of stroke between the male and female die members, instead of adjusting the die-block, as before premised, 100 and illustrated in Fig. 9, I may have interchangeable tips of different lengths, as suggested by the dotted lines in Fig. 10, or I may recess the former end somewhat more than is necessary for the normal length of tip-shank 105 and increase the distance from the former end proper at which the tip *k* projects by inserting extra plates *k''* and *k'''* between the members, and, if necessary, slot the shank to receive the retaining-screw *k'*, all as shown 110 in Fig. 11.

By preference I provide the piston-rods with guides *l l'*, formed in a single bracket or plate *L*, having clamps *l l'*, engaging, say, four of the tie-rods *F F'*, as seen in Figs. 1, 115 2, and 4, and thus insure proper alinement at all times of the male and female dies.

I have not deemed it necessary to fully illustrate the steam-chests, valves, and cylinders and their respective ports and connections, 120 although in Fig. 1 I indicate valve-eccentrics *m m* on the bosses of the fly-wheels *b b* and valve-rods *n n*, connected thereto and broken off, it being understood that the construction, arrangement, and operation of these well-known instrumentalities may be varied according to judgment and engineering skill 125 without prejudice to principle.

As before stated, the die-block *G* is supported entirely by the tie-rods *F*, *F'*, and *F''*, 130 the tensile strain being through their centers from the point from which the force is delivered—*i. e.*, the crank-shaft—to the point of resistance, which will be the formed mass of

blocks within the forming-tubes or female dies of the die-block. This die-block may be made in one solid piece bored at corners and sides to receive the tie-rods and have the 5 forming-tubes or female dies bored directly therethrough, as shown in Figs. 1 and 2, as such a construction would embody every essential principle of my invention; but I prefer to adopt the construction shown in detail 10 in Figs. 5, 6, 7, and 8, as this will facilitate the ready adjustment and centering of the female dies with the formers. In this arrangement G will indicate the die-block proper, preferably cast in one piece and having 15 two forming-tubes or female dies O and O' therein, (adapted to register with the formers or male dies K and K' before described,) these female dies being of course provided with proper hardened-steel bushings (not shown) 20 the internal diameter of which will be the same from top to bottom, so that the material to be consolidated will not receive any lateral compression after it has been set into a block by the initial vertical stroke of the 25 former or male die; and, furthermore, as the entire work is to be done by a cold operation and to keep down frictional heat I prefer to form one or more water-channels *w* in the interior of the die-block, so that a continuous 30 flow of cold water may be kept up around the molds, *w'* and *w''* being the inlet and outlet pipes, respectively. This die-block G rests upon an internal flange *m* of a supporting-frame M, which in turn is firmly supported 35 by the three sets of tie-rods F F' F'' and the nuts and collars arranged above and below said frame, as shown in the last-named figures of the drawings. The frame is slotted at one side, as in Fig. 5, to permit the water- 40 pipes to pass into the die-block proper, and said frame is also tapped on all four sides to receive any suitable number of adjusting-screws *p* *p'*, whereby the die-block G (which does not entirely fill the frame L) may be con- 45 veniently moved horizontally to insure the proper registration of the female dies O' with the male dies K K' above. I prefer also to adjustably secure a covering-plate Q, having 50 openings to register with the dies, to the upper side of the frame L by means of studs *q* *q'*, as seen clearly in Figs. 6 and 7, to keep the intermediate space clear.

Other means of centering and adjustment may be employed according to judgment; 55 also, the other various details of construction and arrangement of parts of the machine may be modified without departing from the principle or sacrificing the advantages of the invention.

60 I have not illustrated any means of feeding the material to the dies, but may state that I prefer to employ separate hoppers or chutes for the two dies of sheet metal arranged immediately above the die-block and so arrange 65 the feed that the material may gravitate between the die members in successive charges in the manner previously stated.

The theory of operation of the above-described press will be readily understood by reference to the drawings; but I will now 70 briefly explain its practical working, meanwhile premising that it will be the same whether the machine stands vertically or horizontally, and the only differences necessary in the arrangement of parts will be in the 75 mounting of the driving and pressing mechanism, so as to sustain the dead-weight, and the substitution of a cross-feed for the vertical feed of material described, the pressing operation and distribution and direction of working strain being identical in both cases. Steam being admitted to one cylinder, the movement of its piston, cross-head, and connecting-rod causes the crank-shaft and fly-wheels to revolve and the valves to move and 80 bring the other cylinder into operation as well. Then the pistons proceed to work in opposite directions, imparting such movement to the formers or male dies that one will be exercising the formative pressure upon one 85 charge of material in one tube while the other is receding and another charge of material is falling to the mouth of the other tube. When the tubes are fully charged, which becomes the case after a few strokes of both 90 formers, one new block is formed at the upper end of each tube against the yielding resistance offered by the previously-formed blocks still remaining therein, and one finished block (or more, according to the thickness of the blocks, which varies according to 95 differences in density of the raw material) is ejected at the lower end of each tube at each stroke of its former.

In the machine most suitable for cold dry peat the total length of forming-tube may be placed at twelve inches and the actual entrance stroke of the former limited to five inches, and as the stroke of the piston will be fourteen inches and the travel of the crank 105 twenty-eight inches it will be seen that in the double press I have described the whole power of both cylinders is transmitted through the crank-shaft and imparted to each block formed, twenty-three inches of travel being 110 free from resistance in each engine, while its companion comes into play midway of the other's travel, and thus does not impair the speed of operation of the double machine. 115

Another feature of importance in this press 120 and giving a material advantage in pressing peat and other materials which have like variations in density is the absolute certainty of the stroke being always of the same length. The result of this is that though the blocks 125 formed may sometimes differ in length, (which is not objectionable in peat fuel,) they will always receive the same compression against the yielding resistance, and will consequently be evenly solid, a quality highly desirable in 130 this product. The set of the cranks and their cylinder connections also insures the easy avoidance of any loss of speed or power due to the dead-center, as the rectangular ar-

angement insures the coöperation of one cylinder with the other during the operation. Again, the construction described affords ready means of adapting the machine for use with different classes of peat, a material which is shown to vary largely in texture, the products of some bogs being more fibrous and looser than others where the decomposition is more thorough or the origin of formation differs, so as to affect the homogeneity of the mass. The adjustment of the die-block or of the former-tips provides for such variations.

What I claim, and desire to secure by Letters Patent, is as follows:

- 15 1. In a press, the combination with a main frame for carrying the dead-weight and staying the parts, of a main shaft having a crank and fly-wheel, journals and bearings therefor independent of the main frame, a connecting-rod and cross-head in operative connection with the crank, a steam-cylinder having its piston-rod projecting therefrom at both ends, one end of said piston-rod being connected to the cross-head, and the other end of said piston-rod left free to act as a former or male die, a die-block having a forming-tube or female die therein, and tie-rods connecting the crank-shaft bearings and the die-block in such manner that each may afford support to the other in the line of working strain, substantially as and for the purpose set forth.
- 20 2. In a press, the combination with a main frame for carrying the dead-weight and staying the parts, of a main shaft having a crank and fly-wheel, journals and bearings therefor independent of the main frame, a connecting-rod and cross-head in operative connection with the crank, a steam-cylinder having its piston-rod projecting therefrom at both ends, one end of said piston-rod being connected to the cross-head, and the other end of said piston-rod left free to act as a former or male die, a die-block having a forming-tube or female die therein, and tie-rods connecting the crank-shaft bearings and the die-block in such manner that each may afford support to the other in the line of working strain, substantially as and for the purpose set forth.
- 25 3. In a press, the combination with a main frame for carrying the dead-weight and staying the parts, of a main shaft having a crank and fly-wheel, journals and bearings therefor independent of the main frame, a connecting-rod and cross-head in operative connection with the crank, a steam-cylinder having its piston-rod projecting therefrom at both ends, one end of said piston-rod being connected to the cross-head, and the other end of said piston-rod left free to act as a former or male die, a die-block having a forming-tube or female die therein, and tie-rods connecting the crank-shaft bearings and the die-block in such manner that each may afford support to the other in the line of working strain, substantially as and for the purpose set forth.
- 30 4. In a press, the combination with a main frame for carrying the dead-weight and staying the parts, of a main shaft having a crank and fly-wheel, journals and bearings therefor independent of the main frame, a connecting-rod and cross-head in operative connection with the crank, a steam-cylinder having its piston-rod projecting therefrom at both ends, one end of said piston-rod being connected to the cross-head, and the other end of said piston-rod left free to act as a former or male die, a die-block having a forming-tube or female die therein, and tie-rods connecting the crank-shaft bearings and the die-block in such manner that each may afford support to the other in the line of working strain, substantially as and for the purpose set forth.
- 35 5. In a press, the combination with a main frame for carrying the dead-weight and staying the parts, of a main shaft having a crank and fly-wheel, journals and bearings therefor independent of the main frame, a connecting-rod and cross-head in operative connection with the crank, a steam-cylinder having its piston-rod projecting therefrom at both ends, one end of said piston-rod being connected to the cross-head, and the other end of said piston-rod left free to act as a former or male die, a die-block having a forming-tube or female die therein, and tie-rods connecting the crank-shaft bearings and the die-block in such manner that each may afford support to the other in the line of working strain, substantially as and for the purpose set forth.
- 40 6. In a press, the combination with a main frame for carrying the dead-weight and staying the parts, of a main shaft having a crank and fly-wheel, journals and bearings therefor independent of the main frame, a connecting-rod and cross-head in operative connection with the crank, a steam-cylinder having its piston-rod projecting therefrom at both ends, one end of said piston-rod being connected to the cross-head, and the other end of said piston-rod left free to act as a former or male die, a die-block having a forming-tube or female die therein, and tie-rods connecting the crank-shaft bearings and the die-block in such manner that each may afford support to the other in the line of working strain, substantially as and for the purpose set forth.

formers or male dies at the other end, a die-block having forming-tubes or female dies therein, and tie-rods connecting the crank-shaft bearings and the die-block so that each may afford support to the other in the line of working strain, said tie-rods also intermediately supporting the steam-cylinders, substantially as and for the purpose set forth.

3. In a press adapted to form a succession of blocks against a yielding resistance, the combination with a suitably-journalized main shaft and means for imparting motion and power thereto, of formers or male dies in operative connection with said main shaft, a die-block having forming-tubes or female dies therein registering with said formers or male dies, tie-rods between the main-shaft journals and the die-block arranged so that each shall support the other in the line of working strain, and means whereby the length of stroke between the male and female die members may be regulated, substantially as and for the purpose set forth.

4. The combination with driving mechanism and supports, of the formers or male dies, the die-block having forming-tubes or female dies therein, the frame supporting said die-block, means for adjusting said die-block in said frame, and tie-rods connecting said supporting-frame with supports of the driving mechanism, substantially as and for the purpose set forth.

5. The combination of the die-block G having female dies O, O', and water-channel *w* therein, the supporting-frame L having flange *l*, adjusting-screws *p*, and covering-plate Q, substantially as and for the purpose set forth.

Signed this 2d day of June, 1898.
